UNITED STATES PATENT OFFICE.

FREDERICK D. BUFFUM, OF GARY, WEST VIRGINIA, ASSIGNOR TO EDWARD O'TOOLE,
OF GARY, WEST VIRGINIA.

MINING-MACHINE.

1,182,453.

Specification of Letters Patent.

Patented May 9, 1916.

Application filed January 11, 1910. Serial No. 537,462.

To all whom it may concern:

Be it known that I, FREDERICK D. BUFFUM, of Gary, in the county of McDowell and State of West Virginia, have invented 5 certain new and useful Improvements in Mining-Machines, of which the following is a specification.

This invention relates to a machine for cutting headings in mines and for removing the mineral cut as fast as it is broken away from the end wall of the heading. In principle the machine is of the same type as the mining machine illustrated and claimed in the application for patent made by Edward 10 O'Toole, Serial No. 378,378, filed June 11, 1907, in that the cutting is done by bits or cutting tools which are attached to laterally moving conveyers and at the same time are reciprocated vertically by the swinging motions of a head on which the cutter carrier 15 is mounted. The arrangement of actuating mechanisms for swinging the head and driving the cutter carrier or conveyer, as well as for removing the cut mineral and 20 propelling the machine as a whole, are different from the parts in the pending application referred to.

In designing the present machine my object has been to provide a simple and 25 stronger machine, which will be adequate to all demands put upon it, to provide means for oscillating the cutter carrier head in such manner that the driving motor may be secured in an unchangeable position upon the frame of the machine, to provide means 30 for more readily adjusting the position of the arc through which the cutters swing, and of varying the extent of such arc independently, to enable the same machine to cut 35 headings of different height without lowering the floor of the heading and without requiring adjustment of the connections which govern the position of the arc through which the cutter head swings, to modify the means 40 for driving the machine in such manner that the driving wheels may also serve for steering the machine around bends, and to modify and improve the machine generally, as 45 will appear from the following specification 50 and claims.

Referring to the drawings, Figure 1 represents in side elevation a machine of the character above indicated, embodying the principles of my invention. Fig. 2 is an 55 elevation of the rear part of such machine,

showing the rearwardly extending horizontal conveyer guide and cars in position to receive mineral discharged therefrom. Fig. 3 is a plan view of so much of the machine as is shown in Fig. 1. Fig. 4 is a sectional view taken on the line 4—4 of Fig. 1. Fig. 5 is a side elevation of the parts shown in Fig. 4, these last two views being on an enlarged scale and further illustrating the parts shown in Fig. 1. Fig. 6 is a rear elevation of the machine as seen from the left of Fig. 1, the conveyer guide being in section. Fig. 7 is a detailed elevation of a part of the driving mechanism by which the machine is propelled. Fig. 8 is another detail 60 of this mechanism on an enlarged scale. Fig. 9 is an enlarged sectional view of the conveyer taken on the line 9—9 of Fig. 2. Fig. 10 is a sectional view of the cutter head on the line 10—10 of Fig. 3, showing the 65 take-up for the cutter chain or conveyer. Fig. 11 is a cross-section of the same on the line 11—11 of Fig. 3.

The same reference characters indicate the 70 same parts in all the figures.

The machine consists of a main frame 1, which is supported by axles 2, 3, on which are mounted traction wheels 4, 5. This frame consists mainly of vertical parallel side plates and supports all the operating 75 parts of the machine. On the forward end of the frame, on the side members thereof, are bearing boxes 6, 7, in which are journaled hubs 8 of the side arms 9 and 10, carrying the cutter bar 11, which, together with 80 the side arms, constitutes the oscillating cutter head. This cutter bar consists of two parallel plates 11^a and 11^b, between which are contained the sprocket wheels 12 and 13, over which the cutter conveyer 14 passes. 85 The sprockets are arranged at opposite ends of the cutter bar, the plates of which are spaced apart sufficiently to receive them, and the cutter conveyer is a chain consisting alternately of blocks 15 and links. The blocks 90 project from the opening between the plates 11^a and 11^b of the cutter bar, and carry bits or cutting tools 17, which are held at such an angle by the blocks that they extend approximately radial with respect to the path 95 of the cutter head, that is, perpendicular to the arc-shaped face of the heading. The edges of the guideway of the cutter bar are provided with guiding strips 18, 19, as shown in Figs. 3 and 11, and the blocks 15 which 100

110

carry the tools or bits have lips or flanges 20, 21, which overlie and embrace these guides. Thus the blocks are prevented from being deflected by the resistance of the mineral, as the cutter head swings up and down, and twisting of the chain is avoided. At the ends of the cutter bar the sprockets and the changing direction of the chain prevent the twisting and overturning of the chain and 10 bits, so that the guides 18, 19 are not needed at these points.

The means for operating the cutter head to keep the chains continuously in motion and also to oscillate the head, as well as to 15 drive the other parts of the machine is, in the embodiment of the invention here shown, a double air motor, consisting of two cylinders with associated cranks, connecting rods and valve mechanism. The motor is virtually two independent engines connected to a common shaft and supplied with compressed air or other working agent from the same source. The engine cylinders are represented by 22 and 23 and are secured upon the 20 outer sides of the frame side members, being bolted thereto. Each engine has a piston in its cylinder driving a crosshead 24 through a piston rod 25 and connecting through connecting rods 26 with a crank 30 shaft 27. In the valve chest 28 of each engine is an ordinary slide valve operated by a valve rod 29, through a rocker 30, and eccentric rod 31 from an eccentric 32 on the shaft. The air for driving the motor is carried 35 through the heading in a hose which follows the machine and is connected to a pipe 34 upon the frame of the machine, in which is a throttle valve 35. The pipe leads to a union 36 in which is a valve controlled 40 by a centrifugal governor 37 driven by a chain 38 from the crank shaft 27, and from which the air is distributed through pipes 39 to the valve chests of the respective agents. The air exhausted from the motor 45 serves to ventilate the mine.

The cutter carrying chain 14 is driven by the air motor through a pivot shaft 40, which is journaled in the hubs 8 of the cutter head side arms 9 and 10. This shaft has 50 keyed to it a gear 41 with which meshes a spur pinion 42 on the crank shaft 27. Loosely mounted upon the pivot shaft 40 near one end thereof is a bevel gear 43 meshing with a complementary bevel gear 44 on a shaft 45. 55 The latter shaft is directly connected to the sprocket 12 about which the cutter chain passes. A clutch 46 mounted upon the shaft 41 and operated by a lever 47 connects the gear 43 with its shaft and enables power to 60 be transmitted to the cutter chain. The clutch is thrown out when the bits are being set and repaired, in order both to avoid danger of the workmen being hurt in case the engine should be carelessly started up, and 65 to facilitate movement of the chain. The

gears 43, 44 run in grease in a dust-tight casing 48, and the gears 41 and 43 also run in grease in a dust-proof casing 49. The shaft 45 is inclosed in the housing 50 and is parallel with the cutter head side arms 9 and 10. In order to take up looseness of the cutter chain due to wear the sprocket 13 is mounted so that it may be adjusted longitudinally of the cutter bar 11. To this end the stud 51 upon which the sprocket is journaled, passes through slots 52 in the inner and outer plates of the cutter bar and is held in sliding plates 53 which are guided on the outer sides of the cutter bar. An adjusting screw 54 (Fig. 10) has a neck portion 55 journaled in a swivel block 56 and is threaded into a nut 57. The ends of the swivel block 56 and nut 57 are turned down to form trunnions which are journaled respectively in the sliding plates 53 and in the cutter bar 80 plates 11^a and 11^b. A capstan head 58 is formed on the screw into the holes of which a bar may be inserted for turning the screw.

It will be observed from Figs. 1 and 3 that with a cutter head constructed as shown and described, all the bits or cutting tools are in action simultaneously, and that less length of chain is necessary than in the form employing two chains in which only one stretch of each is operative at one time. It 95 is possible, however, to substitute a different type of cutter head; for instance one having two cutter carrying chains; and for this purpose the boxes are provided with removable caps to permit ready removal therefrom of the hubs of the side arms 9 and 10.

While the cutters are being moved horizontally by the chains to which they are attached, they are also given a vertical motion by the up and down swing of the head. The 105 means for thus swinging the head consists of an adjustable crank and connecting rod motion as follows:—On the pivot shaft 40 is a sprocket wheel 60 from which a chain 61 passes to a sprocket 62 on a shaft 63. 111 This shaft has keyed to it on each side of the machine spur pinions 64, which mesh with the large gears 65 on a parallel shaft 66, which I term the crank shaft. Slackness of the chain 61 is taken up by an idle 115 sprocket 67 which is vertically adjustable in a slot 68 formed in a bracket 69. On the crank gears 65 secured upon the shaft 66 are crank pins 70 which carry connecting rods 71 pivotally connected with link blocks 72. 120 There are two of these blocks on each side of the machine arranged in pairs, the members of each pair being connected by a wrist pin with which the connecting rod is engaged. These link blocks 72 are pivoted to rock 125 arms 73 pivoted at their lower ends upon pins 74, which are carried by a slide 75. There are two of the arms 73 on each side of the machine arranged respectively on the outer and inner sides of the link blocks and 130

slide 75, and the construction on each side of the machine duplicates that on the other, so that a description of one will suffice for both. The slide 75 is supported by a bracket 76 which projects out from the machine frame, and its upper part is confined and guided by a bar 77 connected with the bracket by uprights at each end thereof. The bracket and guiding bar are grooved as shown in Fig. 4 and the slide 75 is confined at the top and bottom in these grooves.

The slide is slotted vertically at its center as shown best in Fig. 5, thereby providing a guide 78 for a cross-head 79 carrying a pin 80 to which outer and inner swinging bars 81 are connected. Each of these swinging bars passes through one of the link blocks 72 and is oscillated by the back and forth movement of the latter due to the connect-in rod 71. Pivoted to the upper ends of the swinging bars is a block 82 through which passes the ends of two side rods 83, the opposite or forward ends of which pass through a block 84, pivoted at 85 to an arm 86 of the side arms 9 and 10 respectively of the oscillating cutter head. On the extreme outer ends of the side rods 83 are nuts, which prevent their being withdrawn from the blocks 82 and 84 respectively. Owing to the rotations of the eccentric shaft 63 derived from the motor through the pivot shaft 40 and chain 61 the connecting rods 71 and oscillating bars 81 are moved back and forth and this motion is communicated to the cutter head by the rods 83. The weight of the head is partly counter-balanced by springs threaded upon the side rods. Each of these rods carries a number, preferably five, of sets of concentric helical springs 85^a and 86^a. The springs 86^a which I may call the inner springs, are surrounded and covered by the springs 85^a, which I call the outer springs. In the illustration of Fig. 1 the machine is represented as though one of the outer springs had been removed to show the inclosed inner spring, but in the machine as constructed all of the inner springs are covered and concealed from view. Preferably the inner springs are of opposite pitch than the outer springs 85^a. Between the abutting ends of adjacent sets of springs washer plates 87 are threaded upon the rods. The springs abut at their rear ends against the block 82 and at their forward ends bear against a cage or traveling abutment 88, to the ends of which are fastened ropes 89, the rear ends of which are connected with an anchor plate 90 through eye bolts 91, 92 and turn buckles 93. The swinging bars 81 are connected at their upper ends by a transverse tie bar 94 to afford the greatest possible strength and stiffness, and this tie bar carries rollers 96, over which the ropes are led to prevent chafing thereof, and also for the purpose of

supporting the ropes at such a height above the side rods 83 as to balance the weight of the springs and the cage 88 and so to prevent the side rods from sagging.

I provide for adjusting the position of the arc in which the cutter head swings in order to adjust the grade of the heading, and also provide for adjusting the extent of the swing of the head to vary the height of the heading. These adjustments are accomplished by moving the slide 75 horizontally and the cross-head 79 vertically. For moving the slide 75 I provide two screws 95, 96^a respectively, which are pivoted at 97 and 98 to the slide and extend through worm wheels 99 and 100 which are internally threaded to serve as nuts for the screws. These worm wheels are journaled in a slot in the upright 101 of the forward end of the bracket 76. A worm shaft 102 is transversely journaled in the same upright between the wheels 99 and 100 and extends across the machine carrying on its opposite ends worms 103 and 104 which engage with both wheels 99 and 100 on the opposite side of the machine. Hand-wheel 105 is secured to this shaft and on being rotated serves in an evident manner to move the slide 75 forward or back. This movement of the slides 75 shifts the fulcrum point of the rocking bars 81 and so causes the path of the cutter head to be raised or lowered, whereby the grade of the head may be elevated or slanted downward.

The adjustment for the height of the heading is accomplished by a vertical screw 106 threaded through the cross-head 79 and bearing on its lower end a worm wheel 107. A worm shaft 108 extending across the machine carries worms meshing with the wheel 107 on the screw 106 on each side of the machine and carries on its end a ratchet wheel 109, with which a ratchet 110 engages. Adjustment of the screws 106 raises or lowers the rocking bars 81 through the link blocks 72, thereby varying the distance between these link blocks and the pivotal axis of the bars, whereby the extent of travel of the cutter head and thus the height of the heading may be varied. The arrangement of the parts is such that adjustment for height affects only the upper limit of travel of the head and does not alter its lower limit, whereby the height of the heading may be increased or diminished without changing the level of the floor. These two adjustments may be made simultaneously or independently as desired, and the making of either adjustment does not throw out the other.

The coal or other mineral cut is gathered together and carried to the rear by a conveyer, from which it is dumped into mine cars. The conveyer includes screw conveyers operating directly in rear of the cutter

head to gather the cut material from the sides of the heading, a gathering chute which picks up the mineral from the floor of the heading and a chain conveyer which 5 carries the material upward and rearward through a trough or chute to an elevated position in rear of the machine, whence the material can be discharged into cars. The gathering chute is represented at 111 and is 10 pivoted to the front axle 3 so that its forward end may scrape the floor of the heading and follow the irregularities therein. The conveyer trough consists of a front section 112 directly in rear of the gathering 15 chute, an upwardly inclined intermediate section 113 and a rear elevated section 114. These parts of the conveyer trough are all rigidly connected with and made a part of the machine frame. In addition there is an 20 extension 115 pivotally connected to the rear end of the section 114 and adjustable by means hereinafter described to various heights.

The screw conveyer is represented at 116 25 and consists of right and left helices on the ends of a conveyer shaft 117, which is journaled in brackets 118 on the forward end of the gathering chute. The helices extend from the sides of the gathering chute out 30 wardly approximately as far as the end of the cutter head. This shaft is driven from the pivot shaft 40 by means of a chain 119 passing around sprockets 120 and 121 on the pivot shaft and conveyer shaft respectively. Any slack of the chain 119 is taken up by pulley or roll 122 carried by an arm 123 which swings around the pivot shaft and is actuated by a spring 124 connected at its other end with a plate fastened to the 40 forward end of the gathering chute so as to hold the pulley against the slack side of the chain. Upward movement of the gathering chute due to the pull of the chain 119 is resisted by a spring 125 bearing at its upper 45 end against the under side of a plate 126 and pressing downward on a nut 127 threaded upon a rod 128, which passes through the plate 126 and the lower end of which is secured to a bracket 129 on the forward end 50 of the gathering chute. The pull of the chain has a tendency also to draw down the gathering chute on the opposite side of the machine from that shown in Fig. 1 and this tendency is resisted by the similar spring on 55 a rod 130 (see Fig. 3). Adjustable scrapers 131 and 132 are provided on the forward end of the gathering chute for closing the gaps between the latter and the walls of the heading. These scrapers extend laterally 60 and may be set in or out owing to the fact that they are slotted and bolted to the gathering chute.

The screw conveyer gathers the material in front of the gathering chute, whence it is 65 taken by a scraper conveyer. The latter con-

sists of two chains by which scraper blades are carried. The chains pass around sprockets 133 (Fig. 3) on the screw conveyer shaft 117 and travel therefrom over the bottom of the gathering chute 111, the front conveyer section 112 and under an idler sprocket 134. Thence they travel by the inclined conveyer section 113 into the overhung portion and around an end sprocket 135. The upper stretches of the conveyer chains are carried over an idler 136 at the upper end of the inclined section 113 and under an idler 137 at the lower end of this section. The inclined portion 113 of the conveyer trough merges with the raised portion 114 on an 80 arc of large radius and gradual curvature, so that the conveyer scrapers are enabled to travel over this part of the trough with the minimum of resistance. The course of the conveyer chains is indicated by dot and dash lines in Figs. 1, 2 and 3 to avoid complicating the drawings by a complete representation of the chains with their scraper blades, the chains being designated by the characters 137^a and 137^b respectively. 90

The conveyer trough is shown in detail in Figs. 4, 6 and 9. The bottom of the trough consists of plates 138 contained between the side plates 1 of the main frame, and its sides are formed of channels 139. Guides 140 are 95 provided for the lower stretches of the conveyer chains throughout their entire length, these guides being supported on the bottom of the conveyer trough, while similar guides 141 for the upper stretches of the chains are 100 mounted upon brackets 142 secured to the sides 139. The scraper blades attached at their opposite ends to the conveyer chains are represented at 143. A take-up for the conveyer is provided at the rear end of the 105 overhung section, and consists of adjustable boxes 144 in which the shaft of the rear sprockets 135 is journaled. These boxes are contained in guides 145 in the sides of the rear conveyer section and bear against 110 screws 146 threaded through brackets 147.

The conveyer section 115 is adjustable angularly at its point of connection with the section 114. The connection consists of bolts 148 passing through angles 149 at the abutting ends of these sections, and a double screw 150 engaging nuts 151, carried by the sections. A capstan head 152 is formed upon the screw, whereby the latter may be turned by means of a bar. The vertical shear of the 115 overhung section 115 is taken by bent plates 153 riveted to this section and resting on the lower flanges of the channel bars forming the sides of the section 114.

The point of discharge of the mineral is 120 governed by a sliding gate 154 which lies beneath an opening in the bottom of the overhung section 115. This gate is a reinforced steel plate having angles 155 at its opposite sides. To one of the angles is secured a rack 125 130

156 resting on the flange of the channel side bar on that side of the conveyer trough, and the other angle carries rolls 157 supported by the channel on that side. A pinion 158 5 meshes with the rack 156 and is attached to a stud shaft 159 on which is secured a hand wheel 160. Movement of the gate enables the load to be distributed into the car without requiring the latter to be shifted, and also 10 permits the filled car to be removed and an adjacent empty one to be substituted without spilling coal on the ground between them.

The traction wheels 4 and 5 are driven from the eccentric shaft 63 previously described. This shaft carries two eccentrics 15 161, from which hang eccentric rods 162 carrying a lifter bar 163. This lifter bar supports clevises 165 pivoted to pawl arms 165, which swing loosely about worm shafts 20 166. These shafts carry ratchet wheels 167 fixed thereto, with which pawls 168 (Fig. 8) are carried by the arms 165 engage. Also fixed upon each worm shaft is a worm 169 meshing with a worm wheel 170 loose upon the rear 25 axle. The traction wheels 4, which are mounted upon the rear axle, are engaged with said worm wheels, there being one worm wheel for each traction wheel. On the outer ends of the rear axle are sprocket 30 wheels in driving engagement with the respectively adjacent traction wheels, which sprockets drive, by means of chains 173, corresponding sprockets on the forward axle 3 in driving connection with the forward traction wheels 5. The upward movement of the 35 lifter bar acts through the ratchet and pawl mechanism and worm gearing described to give an intermittent forward motion to the traction wheels, the pawls slipping back over the ratchets when the descent of the lifter bar 40 allows them to be lowered.

Various rates of travel of the machine are provided for by limiting the distance through which the lifter bar is allowed to be lowered. It will be observed from Fig. 7 that the ends of the lifter bar are contained in long slots 175 in the eccentric rods 162, these slots being greater than the travel of the rods, so that it is possible to hold the lifter 45 bar stationary in an elevated position without interfering with the movement of the eccentrics. For the purpose of either holding the bar stationary or permitting a limited downward movement I provide stop arms 50 176, pivoted by means of a rod 177 to the frame, which extend under the lifter bar and are connected at their rear ends to rods 178 adjustably held in brackets 179. By adjusting the rods 178 by means of nuts as shown 55 60 in Fig. 7, the stop arms 176 may be located so as either to prevent motion of the lifter bar altogether, or to limit such motion so that the pawl 168 is enabled to drop back over one, two, three, or more ratchet teeth respectively. 65 Thus the travel of the machine may be

stopped altogether, or it may be made any amount up to the predetermined maximum.

The pawl and ratchet drive is made so that the machine may run either backward or forward. For this purpose the clevises 70 164 are loosely hung on the lifter bar so that the pawl arms may be swung to either side of the ratchet wheels and the clevises will move along the lifter bar accordingly. The pawl 168 is made so that it may act in either 75 direction, as shown in Fig. 8, having for this purpose two toes and a central projection 180 on its back. This projection is engaged by a V-pointed pin 181 yieldingly pressed inward by a spring 182, so as to permit the necessary 80 yield of the pawl in traveling back over the ratchet, and to permit either toe to be made operative. The pressure of the pin and spring is adjusted by means of a set screw 85 threaded into the outer end of the socket 183 in which the spring and pin are contained. A socket 184 is formed in the pawl arm so that a bar may be inserted for working the ratchet and moving the machine by hand. The advantage of having the traction wheels 90 independently driven either forward or backward is to enable the machine to be steered to carry it around curves and also to widen the heading. By backing the machine a sufficient distance and then driving it ahead 95 on an angle, the heading may be widened sufficiently to put in a switch for car storage.

The axles are attached to the machine frame by pedestals 185, the traction worm shafts are journaled in bearings 186 joined 100 to a bracket 187 riveted to the adjacent side plate of the machine frame.

Car-hauling is done by winches 188 on the eccentric shaft.

In designing this machine I have had in mind to provide sufficient strength to withstand the shocks and varying strains incident to the variation in the hardness of the material upon which it is to operate. Although the machine is intended mainly for coal mining, yet the necessity of cutting harder mineral must be provided for, owing to the fact that bands of slate and the like occur between the seams of coal. For this purpose the framing has been made of great 110 strength throughout and suitably braced wherever severe strains occur. The material of construction is entirely steel except for bronze journal bushings, cast iron sprockets in the conveyer, and some babbitt bearing 115 linings for the traction wheels and eccentric rods. The cutter head is partially counterbalanced by the springs 85^a and 86^a before described, in order to relieve the driving mechanism as far as possible from excessive work in raising the cutter head, and partially to equalize the power required for the up and down strokes thereof. Enough of the weight of the head is left unbalanced to enable it to overcome the resistance of the 120 125 130

bits in the mineral during the downstroke of the head. The work put on the driving mechanism for raising the head, therefore, is only that required to overcome this unbalanced weight, plus the resistance of the cutters or bits in the mineral. The object of this is to relieve the side rods 83 of compression and cause them to be subjected only to tension. These rods are so long that if any material compression stress were put upon them they would be deflected.

As the head rises from the position shown in Fig. 1 toward a horizontal position, its center of gravity moves outward and acts on a longer arm, and the compression of the springs at the same time diminishes, but they will act at an increasing distance from the pivotal center of the head owing to the fact that the connection with the head is set in front of the pivot shaft and that the links are thereby raised above the pivot shaft. The proportions of these parts are such as to cause the unbalanced weight of the head to remain practically constant.

25 I claim,—

1. In a mining machine the combination of a main frame, a cutter head oscillatively mounted on said main frame comprising arms radial to the axis of oscillation and a cutter guide in a plane parallel to said axis and perpendicular to said arms, a cutter carrying chain located in said guide, and bits carried by said chain and projecting therefrom.

35 2. In a mining machine the combination of a main frame, a cutter head oscillatively mounted on said main frame comprising arms radial to the axis of oscillation and a cutter guide in a plane parallel to said axis and perpendicular to said arms, a cutter carrying chain located in said guide, and bits carried by said chain and projecting therefrom, a shaft rotatively mounted in the axis of oscillation of said cutter head, and a second shaft extending from near one end of said guide toward and into driving mesh with the first named shaft, and a sprocket in the plane of said guide secured to said second shaft for driving said chain.

45 3. A mining machine comprising a frame, a cutter head pivotally attached to said frame so as to swing up and down, a driving motor, a crank driven rotatably by said motor, a rocking member oscillated continuously by said crank, a link connection from said rocking member to said head, whereby the latter is swung about its pivot, and a counter-balancing spring acting upon said oscillating member and tending to move the same in such direction as will elevate the cutter head.

4. A mining machine including an oscillating cutter head, a driving motor connected with said head for swinging the same back and forth, mechanism through which

continuous motion of the motor causes the head to reverse its motion automatically, and a spring bearing upon said head tending to swing the same in one direction.

5. A mining machine comprising a body, a cutter head pivotally attached to the forward end of said body, a rocker having engagement with said head at a point eccentric to the axis thereof, means for oscillating said rocker, and a means for shifting the position of such rocker to alter the position of the arc in which the cutter head swings.

6. A mining machine comprising a body, a cutter head pivotally attached to the forward end of said body, a rocker having engagement with said head at a point eccentric to the axis thereof, means for oscillating said rocker, and a means for altering the extent of swing of said rocker to change the extent of swinging of the head.

7. A mining machine comprising a body, a cutter head pivotally mounted upon said body and arranged to swing about its pivot, a driving crank, an intermediate rocker between said crank and cutter head, connecting rods extending from said rocker to said crank and cutter head respectively whereby oscillating movement is transmitted to the head, and provisions for changing the distance between the fulcrum of said rocker and the point of connection with one of said connecting rods.

8. A mining machine comprising a body, a cutter head pivotally mounted upon said body and arranged to swing about its pivot, a driving crank, an intermediate rocker between said crank and cutter head, connecting rods extending from said rocker to said crank and cutter head respectively, whereby oscillating movement is transmitted to the head, and means for shifting the fulcrum point of said rocker to vary the position of the path of the cutter head.

9. A mining machine comprising a body, a cutter head pivotally mounted upon said body and arranged to swing about its pivot, a driving crank, an intermediate rocker between said crank and cutter head, connecting rods extending from said rocker to said crank and cutter head respectively, whereby oscillating movement is transmitted to the head, and means for shifting the point of connection between said rocker and one of said connecting rods whereby the amplitude of swing of the cutter head may be varied.

10. A machine for cutting passage ways in mines, comprising a movable body, a cutter head mounted pivotally upon said body to swing across the face of the opposing material at the end of the passage way, mechanism for so swinging said cutter head, means for shifting the path in which said cutter head swings, whereby to alter the grade of the passage way, and means for varying the upper limit of travel of the

head, whereby the height of the passage way may be varied.

11. A mining machine comprising a main frame, traction wheels by which said frame is supported, a cutter head mounted upon the forward end of the machine so as to swing up and down, mechanism for rotating said traction wheels to drive the machine forward, and mechanism for swinging said head up and down, said mechanism including means operable while the machine is in motion for altering the amplitude and the position of the travel of the cutter head.

12. A mining machine comprising a body, a cutter head attached to said body in such manner as to oscillate about a generally horizontal axis, mechanism including a crank, a connecting rod, a rocker engaged with said connecting rod and connected to the head, for oscillating said cutter head, and means for changing the distance between the fulcrum of said rocker and the point of its engagement with said connecting rod to vary the extent of travel of the cutter head.

13. A mining machine comprising a body, a cutter head, a driving crank, a pivoted rocker, a connecting rod between said crank and rocker and a connecting rod between said rocker and cutter head, the fulcrum of said rocker being adjustable in the direction of the second connecting rod to shift the location of the path in which the cutter head travels.

14. A mining machine comprising a body, a cutter head, a driving crank, a pivoted rocker, a connecting rod between said crank and rocker, and a connecting rod between said rocker and cutter head, the points at which said rocker is engaged with the connecting rods being at respectively different distances from its fulcrum.

15. A mining machine comprising a body, a cutter head, a driving crank, a pivoted rocker, a connecting rod between said crank and rocker, a connecting rod between said rocker and cutter head, and means for varying the distance between the point at which one of said connecting rods is engaged with said rocker and the fulcrum of the latter, whereby the amplitude of swing of the cutter head may be varied.

16. A mining machine comprising a main frame, a cutter head pivotally connected with said frame so that it may oscillate thereon, a rocker, a connecting rod between said head and rocker, a driving crank and a connecting rod engaged with said crank and rocker, the parts being so arranged that when at one limit of their travel the rocker is approximately perpendicular to said connecting rods, whereby the distance between the fulcrum of said rocker and the point of its engagement with one of said connecting rods may be varied without moving the cutter head.

17. A mining machine comprising a main frame, a cutter head pivotally connected with said frame so that it may oscillate thereon, a rocker, a connecting rod between said head and rocker, a driving crank and a connecting rod engaged with said crank and rocker, and means for varying the distance between the fulcrum of said rocker and the point of engagement between the latter and one of said connecting rods, whereby the amplitude of swing of the cutter head may be varied, the said parts being so arranged that when in one limit of their travel the rocker is approximately perpendicular to the connecting rods, whereby said variation between the connecting rod and rocker alters only one limit of travel of the cutter head.

18. In a mining machine a swinging cutter head, a driving crank, a pivotally mounted rocker, connecting rods extending from said crank and cutter head respectively to said rocker and engaged therewith, and means for shifting the pivotal support of said rocker in two directions at right angles to each other, whereby the amplitude and position of the path of travel of the cutter head may be varied.

19. In a mining machine a swinging cutter head, a driving crank, a pivotally mounted rocker, connecting rods extending from said crank and cutter head respectively to said rocker and engaged therewith, and means for shifting the fulcrum of said rocker longitudinally of the machine, whereby the position of the path of movement of the cutter head, and consequently the grade of the heading, may be varied.

20. In a mining machine a swinging cutter head, a driving crank, a pivotally mounted rocker, connecting rods extending from said crank and cutter head respectively to said rocker and engaged therewith, and means for moving the pivotal point of said rocker toward and from the point of connection between the rocker and one of said connecting rods, whereby the amplitude of swing of the cutter head may be varied.

21. In a mining machine, a cutter head mounted to move in an arc across the face of the material in front of the machine, sprocket wheels mounted on said head in a plane tangent to such arc, a cutter-carrying chain passing over said sprocket wheels, being thereby held with both stretches parallel to and equally distant from the axis of oscillation of the head, cutters or bits secured to said chain and projecting forwardly from the plane occupied by the chain, a shaft coaxial with the center of said arc, and a second shaft radial to said arc driven by the first shaft, and connected to one of said sprockets to drive the chain.

22. In a mining machine a frame, a cutter head pivoted to said frame having a guide

upon its outer or swinging end, a chain arranged in said guide, cutting tools or bits secured to said chain, sprocket wheels about which said chain is carried, a shaft arranged 5 concentrically with the axis of said cutter head and a second shaft geared to said first-named shaft and connected with one of said sprockets for driving the chain and cutters.

23. In a mining machine the combination
10 with the frame of said machine of an arm pivotally connected on said frame so as to oscillate thereon, a cutter guide secured to the outer end of said arm, sprockets carried by said cutter guide in a plane perpendicular to said arm, a chain passing about said sprockets, cutting tools or bits secured to said chain, and a shaft parallel to said arm for driving one of said sprockets and thereby driving the chain.
- 15 24. In a mining machine the combination
20

with the frame of said machine of an arm pivotally mounted on said frame, so as to oscillate thereon, a cutter guide secured to the outer end of said arm, sprockets carried by said cutter guide, a chain passing about 25 said sprockets, cutting tools or bits secured to said chain, a pivot shaft arranged concentrically with the pivotal axis of said arms, means for rotating said shaft and a second shaft geared to said first-named shaft 30 and driven thereby, having a connection with one of said sprockets to drive the latter and thereby the chain and cutters.

In testimony whereof I have affixed my signature, in presence of two witnesses.

FREDERICK D. BUFFUM.
